FIG. 4.

FIG. 7.

INVENTOR
Emery J. Wilson

UNITED STATES PATENT OFFICE.

EMERY J. WILSON, OF CLEVELAND HEIGHTS, OHIO.

SPEEDOMETER.

Application filed July 26, 1922. Serial No. 577,730.

This invention relates to speedometers of the liquid-centrifugal type and is an improvement upon the construction described and claimed in my prior applications for rotary speed indicators, Patent No. 1,416,082, filed December 21, 1916; Patent No. 1,466,156, filed March 15, 1917; Patent No. 1,416,083, filed May 29, 1917; and Patent No. 1,416,084, filed June 24, 1918.

In these prior applications I have shown that, in a given container for the liquid having certain of its confining walls of known arbitrary shapes and proportions, the remaining wall or walls can be so shaped with reference to the known factors that predetermined positions of equilibrium of the liquid mass can be established for given speeds of rotation. The improvements shown in the present application relate chiefly to a simplification of the form of the container and to a new arrangement of the parts which permits of a more commercial design for the indicating mechanism and for the driving mechanism which rotates the container and actuates an odometer, and also results in a simplified construction for the main frame which supports the entire mechanism.

The objects of the invention are:—

- (1) To eliminate certain accurate settings required in some of the prior constructions.
- (2) To extend the length of the liquid vortex in the discharge chamber so that the liquid will not have to pass through restricted passages at the low speeds of rotation.
- (3) To obtain substantially uniform scale spacing from the zero point of speed up to that speed at which the compensating or calibration surfaces, described in my prior patents, begin to function, by utilizing the action of molecular attraction inherent in the liquid or existing between the liquid and its supporting surface.
- (4) To provide a more commercial construction for the mechanism which translates the vertical motion of the float to a rotary motion of the dial.
- (5) To support and drive the container at its upper end, thereby raising the point of attachment for the flexible driving shaft to a much more desirable position and permitting the use of a simple means for properly charging the instrument while running.

Further objects of the invention are in part obvious and in part will appear more in detail hereafter.

A specific embodiment of the invention is illustrated in the accompanying drawings in which Fig. 1 is a section through the axis of rotation of the container; Figs. 2 and 3 are enlarged cross sections taken on the lines 2—2 and 3—3 respectively of Fig. 1; Fig. 4 is a part elevation and part section; Fig. 5 is a section on line 5—5 of Fig. 4; Fig. 6 is a detail of plate 42 shown in Fig. 5; Fig. 7 is an enlarged diagrammatic view of a portion of the discharge and central chambers used in describing the operation of the device; and Fig. 8 is a diagrammatic view illustrating the relative pitch lines of the teeth of the co-operating gears 34 and 37.

In Figure 8 I have illustrated the pitch relation of the teeth of co-operating gears 34 and 37, the dot and dash line "x" indicating the axis of the driving shaft 35, the dot and dash line "y" indicating the axis of the insert 31 (by which gear 34 is carried), and cap 24; in fact, the line "y" indicates generally the axis of rotation of the mercury-carrying parts of the speedometer. The two gears are shown as adapted to travel at similar speeds. Owing to the difficulty of attempting to show a true section of the teeth of gear 34 in Fig. 1, and of the teeth of gear 37 in Fig. 4, the teeth of these gears in these views are shown conventionally as spur teeth; it is to be understood, however, that the true pitch line of the teeth of these gears, in the embodiment shown in the drawings, is illustrated in Fig. 8.

In the drawings 1 indicates the main frame of the instrument. A rigid post 2 is held fixed in the frame by nut 3 and is formed to provide an extended length of journal 4 and enlarged lower end 5 to which is rigidly attached the tube 6. A plug 7, fitting tight in the lower end of the tube, serves to support the cam rod 8, the upper portion of which is reduced in diameter where it passes centrally through a clearance hole in the post, and carries a tight fitting spindle 9 which has a bearing 10 in the top end of the post. A dial 11 is adjustably mounted on the upper end of the spindle and clamped thereto by lock nut 12. The tube 6 forms a central chamber 13 containing a non-rotatable column of mercury on which rests a float 14 which is adapted to move up and down in the tube as mercury flows to and from the central chamber. The float carries at its lower end a plate 15 with radial projections 16 which slide in

straight vertical grooves 17 machined on the inside of the tube, and at its upper end a tight fitting pin 18 and adjusting screw 19, said pin and screw having their inner ends conical 5 and adapted to slide along V-shaped helical grooves 20 in the cam rod 8. The whole arrangement is such that the dial 11 rotates through equal angles as the float moves vertically through equal distances. In this arrangement it is to be noted that clearance spaces 21 and 22 (Fig. 2) are provided between the float and tube, and between the float and the cam rod, and that the upper end of the float is guided entirely by the pins 18 10 and 19 working in the cam grooves, while the lower end of the float is guided entirely by the projections 16 working in the tube grooves 17, so that the float can adjust itself to inaccuracies of alignment which may exist between the cam rod and tube. 15

The rotating receptacle comprises a body 23 and tight fitting cap 24 which, with the outer cylindrical surface 25 (radius= R_1) of the tube, form a discharge chamber 26 which is in constant liquid communication with the central chamber 13 through vertical and radial grooves 27 and 28 formed in the body 23, and through the axial hole 29 and radial holes 30 formed in the bottom plug 7. Cap 24 carries a tight fitting insert 31 which has a bearing on journal 4 and is provided at its lower end with a ball bearing 32 supported on the enlarged end 5 of the post 2, so that the rotating receptacle is centered upon and entirely supported by the post, and is rotatable about the fixed tube 6. The insert 31 extends upward from cap 24 into a pocket 33 of frame 1, and forms a spiral toothed gear 34 at its upper end. An inclined driving shaft 35 (Fig. 4), supported in bearings 36 of frame 1, carries another spiral toothed gear 37 which meshes with gear 34, and a worm 38 which meshes with worm gear 39 having its journals 40 and 41 supported respectively in frame 1 45 and cover plate 42 attached to said frame by screws 43. Parts 38 to 44, together with parts of other structures shown, pertain more particularly to an odometer mechanism which may be employed in connection with the present invention. 50

In Figure 8 I have illustrated the pitch relation of the teeth of co-operating gears 34 and 37, the dot and dash line "x" indicating the axis of the driving shaft 35, the dot and dash line "y" indicating the axis of the insert 31 (by which gear 34 is carried), and cap 24; in fact, the line "y" indicates generally the axis of rotation of the mercury-carrying parts of the speedometer. The two gears are shown as adapted to travel at similar speeds. Owing to the difficulty of attempting to show a true section of the teeth of gear 34 in Fig. 1, and of the teeth of gear 37 in Fig. 4, the teeth of these gears in these views are shown conventionally as spur teeth; it is to be under-

stood, however, that the true pitch line of the teeth of these gears, in the embodiment shown in the drawings, is illustrated in Fig. 8.

In this invention the proper formation of the surface 47 lying at the periphery of the discharge chamber below the surface of the mercury when the instrument is at rest, is a particular feature, for this surface can be so shaped that the molecular attraction of the mercury will function at the initial speeds in such a manner that a uniform scale spacing on the dial, clear down to the zero point of speed, will correctly indicate these low speeds of rotation. This surface is in effect another compensating surface. It would be difficult and probably impossible to derive exact mathematical formulæ for the shape of this surface, even though the laws of molecular attraction were well known, but it is quite possible to determine empirically this shape with sufficient accuracy for all practical purposes since it functions only at the very low speeds. 75

It is well known that mercury resting on a flat horizontal surface tends to remain collected into a single mass of considerable depth with its edges rounded under to the point of contact with the supporting surface. If the supporting surface be slightly dished to a concave spherical form, the mercury mass will assume the form of a round flattened disc. 90 If this disc is rotated slowly about a vertical axis the centrifugal force of the mercury tending to spread it out acts against its inherent molecular attraction which tends to keep it from so spreading. The point at 95 which balance takes place for any particular speed depends on the slope of the supporting surface. By varying this slope the desired predetermined positions of equilibrium of the mercury mass can be established. It is of course understood that the tendency of the top surface of the mercury to form a vortex exists at all speeds. 100

Referring to the diagrammatic view Fig. 7, the zero level of the mercury when the instrument is at rest is at the line $x-x$, its outer peripheral edge assuming the curved form as noted above and as indicated at 48, due to molecular attraction; so that an open space 49 is formed at the periphery of the discharge chamber below the zero level of the mercury. This space 49 is bounded by the surfaces 47 and 50^a of the receptacle, and the mercury surface 48; and its volume must necessarily be equal to the volume of liquid bounded by the line $x-x$, the vortex curve n_1 , the surface 50^a of the receptacle, and that portion of the mercury surface 48 which lies above the vortex curve n_1 . An air duct 46, Fig. 1, uniting the space 49 to the space in the discharge chamber above the zero line, is needed to permit free movement of air to and from space 49 to prevent pocketing of air or the formation of a vacuum therein. During the period when such space 49 is actually 115

110

115

120

125

130

present, air can pass between it and the portion of the chamber above the liquid level; with the elimination of the space by the presence of liquid therein, there is no further need for the activity of the duct and it becomes closed by the liquid until the level of the latter again passes to the top plane of the space 49 at which time the duct 46 is again active for the transfer of air.

10 The empirical derivation of the curve 47 consists of a cut and try method. By starting with an approximate contour for this surface, the receptacle is rotated at successively increasing speeds and the corresponding displacements of the float from its zero position are noted. If the movement of the float corresponding to an increase of speed dn is less than the desired value ldn , the slope of that portion of the curve 47 just passed over by the mercury is too steep; if the movement is greater than ldn the said slope is not great enough. l =the assigned uniform movement of the float for one R. P. M. change of speed. By using a suitable material such as paraffin as a lining for this part of the experimental container, the derivation of the surface 47 is facilitated. It is of course understood that when the proper shape of the surface 47 is once determined it can be permanently incorporated in the die used for moulding the body 23, so that this feature of the construction adds nothing to the manufacturing cost of future instruments.

35 The primary object of the surface 47 is two-fold: First, to produce a free space in the discharge chamber below the level of the liquid when the instrument is at rest, into which space the mercury can flow when the instrument starts to rotate, and from which the mercury can be drawn by molecular attraction as the speed of rotation approaches zero; and second, to elevate the float to that point from which its movement is proportional to the speed of rotation, namely, the line $x-x$, 40 so that the scale spacing from 0 to say 5 miles per hour will be of the same length as other 5-mile portions of the scale. This will be clearly understood by reference to Figs. 16 and 17 of my Patent Number 1,416,084 in which no such surface as 47 exists, and consequently the zero level of the mercury must come below the line $x-x$, with the result that the scale from 0 to 5 is much less than it is from 5 to 10. The secondary object of the surface 47, namely, the obtaining of an exactly uniform scale spacing over this low range of speed from 0 to 5, is simply a further refinement of operation.

50 The operation of the instrument is as follows:

(1) As the speed increases from n (R. P. M.)=0 to $n=n_1$:

The outer edge 48 of the mercury in the discharge chamber moves outward and upward along the surface 47 until the top free

surface of the mercury mass assumes the position indicated by the vortex curve n_1 . The top surface of the mercury in the central chamber remains a plane surface tangent at the vertex of the changing vortex in the discharge chamber, and moves downward through the distance $H_1=ln_1$. Throughout this range of action the float moves through equal distances for equal changes of speed, due to the functioning of the surface 47.

70 (2) As the speed increases from $n=n_1$ to $n=\text{maximum}$:—The upper limit of the vortex curve in the discharge chamber travels inward and upward along the calibration surface 50; the lower limit of the vortex curve travels first downward, then upward, along the cylindrical base surface 25 (radius= R_1), and the top surface of the mercury in the central chamber continues to descend through equal distances for equal changes of speed, due to the functioning of the calibration surface as fully described in my prior patents. In Fig. 1 an intermediate position of the float is shown by dotted lines at 14' and the vortex for the speed corresponding to this position is shown at n .

80 The general equations for the coordinates R and x of the curve for this calibration surface 50 are the same as those given on page 5, lines 50-55, of my Patent No. 1,416,084, 85 for curve 57 described therein. The assigned values of the constants R_1 , l and ρ used for curve 57 are however different from those used for the present curve 50. The general equations referred to are:

$$R^2 = \frac{\sqrt{(2cR_1^2n-l)^2 + 4cl\rho^2n^2} + l}{2cn} \quad (1)$$

$$x = cR^2n^2 - ln \quad (2)$$

100 These equations show that the curve 50 is tangent to the zero line $x-x$ at infinity. Fig. 7 shows that it approaches very closely to the line $x-x$ at the finite distance R_0 , the value of x when $R=R_0$ being equal to -.004" for the proportions shown in the drawings, the negative sign indicating that this point of the curve is below the line $x-x$; and the maximum negative value of x is -.015 corresponding to $R=.740"$. If the vortex surface of the mercury were unbroken by the insertion of the fixed tube 6 which prevents the mercury within it from rotating, the curve 50 would become a straight line coinciding with $x-x$.

110 The value of n_1 referred to above is found from equation (1) by setting $R=R_0$ and solving for $n=n_1$.

115 From the above it will be understood that I have provided an improved form for the 125 rotating receptacle for the mercury, in that the restricted passages in the discharge chambers shown in my prior applications have been entirely eliminated, thereby permitting the top surface of the mercury in said chamber 130

ber to form its true vortex more readily. Furthermore, a decided advantage is gained in point of manufacture since the accurate setting of a horizontal base surface with reference to its derived calibration surface is dispensed with; and a surface already existing in the structure is used as a base surface, namely, the outside surface of the fixed tube 6, which does not have to be set to any particular vertical position.

The working parts of the instrument are suitably enclosed in a two-part casing comprising upper half 94 and lower half 95 with its tubular extension 96. Both parts are attached by a number of screws 97 to the U-shaped flange 98 forming a part of frame 1. The usual bezel ring 99, glass 100 and face plate 101 through which the desired portions of the speed scale and odometer are visible, 20 are of usual construction.

In charging and testing the speed indicator it is desirable to have an easy means of supplying and regulating the amount of mercury required for accurate registration of the speeds. If the receptacle is suitably connected to a fixed source of supply this operation can be performed while the receptacle is rotating. Such a connection is indicated at the bottom end of the body 23 and comprises simply a plug 103 which is screwed into the body at the axis of rotation and is adapted to properly fit and rotate about a suitable supply nozzle inserted in the axial hole 104 of the plug. An eccentric hole 105, located in 35 the lower wall of said body, establishes liquid communication between the nozzle and the receptacle when the plug is slightly withdrawn from its seat 106, by means of a suitable spanner wrench. When the proper amount of mercury is introduced into the receptacle, the supply from the nozzle is first 40 shut off, then the rotation of the instrument is stopped, the plug screwed down tight on its seat, the nozzle withdrawn and the plug permanently sealed. By this method the instrument can be quickly and accurately calibrated at any particular speed.

Having described my invention, I claim as new:—

50. 1. In a liquid centrifugal speed indicator having inner and outer communicating chambers for receiving the liquid, wherein the indications are made responsive to the movement of such liquid in the inner chamber, 55 and wherein the outer chamber constitutes a discharge chamber into which the liquid flows upon rotation, said discharge chamber having a normal zero level of the liquid when the instrument is at rest, said discharge chamber 60 including as a portion of its liquid confining walls a surface lying below the plane of such normal zero level and adapted to be traversed by the liquid during movement of the latter when the instrument is in speed-responsive 65 service, the position of said surface being such

that a predetermined cross-sectional area of the chamber between such surface and such plane will be maintained free from the liquid by molecular attraction of the liquid when the instrument is at rest, and contain liquid during speed-responsive movements of the instrument.

2. An indicator as in claim 1, characterized in that the value of the free cross-sectional area of the chamber between such surface and plane is varied in a decreasing direction as the speed is increased.

3. An indicator as in claim 1, characterized in that the value of the free cross-sectional area of the chamber between such surface and plane is varied in a decreasing direction as the speed is increased, with the cross-sectional area eliminated in presence of a speed-value equal to and beyond a definite speed value in such increasing direction.

4. An indicator as in claim 1, characterized in that the value of such predetermined cross-sectional area is reduced to zero in response to a speed value of a predetermined amount and maintained in such condition during periods when the speed value is equal to or greater than that of such predetermined amount.

5. An indicator as in claim 1, characterized in that the value of such predetermined cross-sectional area is reduced to zero in response to a speed value of a predetermined amount and maintained in such condition during periods when the speed value is equal to or greater than that of such predetermined amount, the value of such cross-sectional area being varied in an increasing direction by molecular attraction of the liquid as the speed is decreased from such predetermined speed value.

6. An indicator as in claim 1, characterized in that such lower surface is shaped relative to its opposing liquid-confining wall of that portion of the outer chamber included within the zone of such predetermined cross-sectional area, that the space included within such area will receive such increments of the liquid when rotated as will make the movement of the liquid in the inner chamber proportional to the speed of rotation, due to the conditions of molecular attraction present within the outer chamber.

7. In speed indicators, wherein a confined liquid mass is subjected to centrifugal action to produce characteristics of a vortex, wherein the carrier for the liquid mass is formed to provide inner and outer chambers in permanent communication and with each chamber having a free liquid surface of the mass, the free surfaces being in permanent connection through the body of the mass, and wherein the indications are made responsive to the changes in position of the free liquid surface of the mass of the inner chamber, means operative to establish definite positions

of equilibrium of the mass at definite speeds of rotation in presence of mass increment flow produced by variations in speed, said means including a succession of faces of the outer 5 chamber positioned to be traversed successively by free liquid surfaces operating in said chamber, one of said faces lying below the plane of the normal zero level of the liquid within such outer chamber.

10 8. An indicator as in claim 7, characterized in that other of the faces traversed by a free liquid surface operating in the outer chamber are located above such normal zero level of the liquid within the chamber.

15 9. In a centrifugal speed indicator wherein the speed is evidenced by a rotatable indicator made responsive to the vertical movement of said liquid, means for translating the said vertical movement of the liquid to 20 said rotatable movement of the indicator, said means comprising a float supported by

said liquid, a rotatable rod carrying said indicator, a fixed member supporting said rod, and means for causing float movements to be translated into rotational movements of the 25 rod, said latter means including spaced-apart elements carried by the float and adapted to traverse a vertical groove of the fixed member and a helical groove of the rod respectively, said elements including an adjusting 30 screw having a conical exposed end co-operative with a groove, such groove being V-shape in cross-section to be complementary to such conical end, said screw being located materially above the lower face of the float, 35 the element which co-operates with the groove of the fixed member being located in proximity to such lower face of the float.

In testimony whereof I hereby affix my signature.

EMERY J. WILSON.
